ADJUSTABLE ROTARY CIRCUIT CONTROLLER

Filed Aug. 12, 1921

FIG. 1.

FIG. 3.

FIG. 2.

FIG. 4.

R. C. Leake, Inventor
By his Attorney,
Neil H. Preston

UNITED STATES PATENT OFFICE.

RICHARD C. LEAKE, OF ROCHESTER, NEW YORK, ASSIGNOR TO GENERAL RAILWAY SIGNAL COMPANY, OF GATES, NEW YORK, A CORPORATION OF NEW YORK.

ADJUSTABLE ROTARY CIRCUIT CONTROLLER.

Application filed August 12, 1921. Serial No. 491,779.

To all whom it may concern:

Be it known that I, RICHARD CHASE LEAKE, a citizen of the United States of America, residing at Rochester, in the county of Monroe and State of New York, have invented certain new and useful Improvements in Adjustable Rotary Circuit Controllers, of which the following is a specification.

10 In circuit controllers of the sectional drum type, particularly those used in railway signalling systems, it is highly desirable to be able to accurately adjust the individual drums of the circuit controller, and at the same time maintain the drums securely connected to the shaft or other operating element so that they can not get out of proper adjustment in service. Also, the provisions for adjustment should 15 preferably be such that the drums will not be loose or be able to shift to any great extent from the proper adjusted position, in case of careless or accidental manipulation.

20 One of the objects of the present invention is to provide a construction of a sectional drum circuit controller in which the several drums are connected to the operating shaft by individual adjustable fastening 25 connections, so that each drum may be easily adjusted by a simple manipulation without disturbing the adjustment of the other drums.

Another object is to provide an adjustable fastening connection for each drum which will permit small increments of adjustment for any position of the drum on its shaft, while at the same time possessing the necessary strength and durability.

30 A still further object of the invention is to provide an adjustable fastening connection for each drum which will not allow the drum to work loose on the shaft in service and which will also prevent the drum from 35 moving to any great extent from its proper adjusted position in case of breakage or misadjustment.

Another object is to provide a construction in which the elements of the adjustable fastening connection of each drum are 40 accessible from the same side of the shaft,

so that the desired adjustments can be readily made without shifting the circuit controller from its ordinary position.

Other objects and advantages will appear 55 as the description of the invention progresses, and the novel features of the invention will be particularly pointed out in the appended claims.

In describing the invention in detail, reference is made to the accompanying drawings, in which several physical embodiments of the invention are illustrated, and in which:—

Figure 1 is a cross-sectional view taken 65 through the axis of several controller drums supported on a shaft;

Fig. 2 is a sectional view of the device taken on the line 2—2 in Fig. 1 looking in the direction of the arrows; 70

Fig. 3 is a view similar to Fig. 2 of a modified form of the invention; and

Fig. 4 is a fragmentary perspective view of a rotary circuit controller having the adjustable fastening means embodying my 75 invention applied thereto.

In Fig. 4 of the drawing I have shown my invention in connection with a conventional type of drum circuit controller comprising a shaft 1 which is journaled in suitable bearings 2 and which may be turned to different positions by some suitable driving connection (not shown). On each side of the controller shaft is a terminal board 3 made of suitable insulating material carrying a spring contact finger 4 for each individual drum 5. Each of the individual drums 5 is provided on its periphery with a contact segment 6 of suitable conducting material arranged to bridge its pair of contact fingers through a particular arc of movement of the controller drum. These contact segments 6 may be of different lengths so as to establish the circuit through their respective contact fingers through different arcs of movement of the shaft. 85 90 95

It will be evident that the length of the contact segment 6 of each individual drum 5 determines the angle or arc of movement of the shaft 1 during which a circuit is established between the contact fingers associated with that drum, while the adjustment 100

of the drum 5 on the shaft determines the point in the movement of the shaft 1 at which this circuit connection is made or broken. In circuit controllers employed in 5 railway systems, to which the present invention more particularly relates, it is highly desirable to be able to determine accurately the point in the rotation of the shaft at which a given circuit shall be made 10 or broken; and since in commercial manufacture there will be slight differences in the length of the contact fingers, the shape of the ends of these fingers and the segments, and other variations, it is proposed, in accordance with the present invention, to provide an adjustable fastening connection between each individual drum 5 and the shaft 1. This fastening connection is the same for each drum, and a description of one will 15 suffice for all.

This fastening means comprises a reinforcing collar 7 having an inwardly radially extending projection 8 which is of the proper size to fit slidably in a keyway 9 formed 25 lengthwise of the controller shaft. Riveted or otherwise fastened to the reinforcing collar 7 is a locking member or disk 10 of resilient material having a plurality of outwardly extending equally spaced spring 30 fingers 11. These fingers 11 are bent so as to tend to spring out from the plane of the body of the locking member 10; and this tendency is preferably attained by giving the locking member 10 a permanent set in 35 a concave or dished shape during its manufacture.

Each drum 5 is formed at one end with projections 12 leaving notches 13 of the 40 same width as the spring fingers 11 which co operate therewith, and the other end of the drum is rabbeted or cut away as shown at 14 in Fig. 1 for the purpose hereinafter explained.

The plurality of adjustable drums 5 are 45 assembled together to form the circuit controller in the following manner. The controller shaft 1 is provided with a pin, nut and washer, or the like, at one end, (not shown) to serve as a stop. Drums 5 and 50 locking members 10 are alternately slipped on the shaft 1 in such a way that the dished portion of the locking member 10 will face the end of the drum 5 provided with projections 12.

55 Since the drums 5 are loose on the shaft 1, they may be turned to the approximate position desired, and when this has been done, the drums 5 are then pressed together by some suitable means, such as a nut 15 threaded on the end of the shaft 1 as shown in Fig. 1. As the drums 5 are thus pressed together, the dished locking members 10 are flattened out and their spring fingers 11 are pressed back, unless the corresponding drum happens to be in the correct posi-

tion to bring some one of the fingers 15 directly opposite a notch 13. After the circuit controller has been assembled in this way, the individual drums 5 may then be separately and accurately adjusted to the 70 desired position.

It is apparent that if the notches are slightly differently spaced than the fingers, some kind of relative adjustment between the shaft 1 and drum 5 is possible. In 75 order that the increment of adjustment may be as small as possible, the difference in spacing between the notches 13 and spring fingers 11 must be as small as possible; and in order to have an uninterrupted series of 80 adjustable positions for the drum for any position on the shaft, there must either be one more or one less notch than finger, and vice versa. This relationship is similar to that of the two scales of a vernier, and may 85 be conveniently called a vernier relation.

This vernier relation provides for accurate adjustment for any position of the drum on the shaft. For example, in Fig. 2, there are shown 12 notches and 11 fingers. 90 The drum 5 and locking member 10 are shown in relative positions where the uppermost finger 11¹ is opposite a notch 13¹. If the drum 5 is turned through a small angle clockwise, the next finger 11² to the 95 right will come opposite the notch 13²; if turned a little farther, the next finger 11³ to the right will come opposite the notch 13³; and so on, until the point is reached where the first finger 11¹ is opposite the next 10 notch 13¹². There is thus provided a rough adjustment from notch to notch and a fine adjustment between notches, depending upon the number of fingers. In the arrangement shown in Fig. 2, the increment of adjustment in degrees is equal to 360 divided by the product of the number of notches and 105 number of fingers. For small increments of adjustment, the fingers and projections should be made as small as the strength of 110 the material will permit, and they must be spaced as close as possible, so that there will be one more finger than notches, or vice versa.

Any one of the several drums 5 may be 115 adjusted without in any way interfering with the adjustment of any other drum. This is done by backing off the nut 15 on the shaft 1 which holds the drums together just enough to remove the friction between 120 adjacent members; and then the engaged finger is pried back with a screw driver or the like, and the drum may then be turned until another finger engages, and so on. This procedure is suitable where only a 125 slight change in adjustment is to be made.

When a coarse adjustment is to be made, the nut 15 is backed off far enough to allow the spring fingers adjacent the particular drum to be adjusted to assume their orig- 130

inal dished shape, the other drums being held together in any desired way so that they will be maintained in their original locked position. The drum in question is 5 now free to rotate on the shaft and may be turned to any desired position, and then the drums may be all forced together by the nut 15 and securely locked to the shaft 1.

The modified form of my invention 10 shown in Fig. 3 is especially advantageous where it is desirable to be able to make an adjustment without turning the controller shaft, especially where only one side of the controller drum is accessible. This arrangement is valuable in those instances 15 where it is impossible to turn the shaft 1 fully around without disconnecting the operating means, or where such turning of the drum would affect the mechanism controlled thereby or is otherwise objectionable. The locking member 10^a in this modified construction is provided with fingers 11^a part way around the shaft only, so that the fingers are always accessible. The relative 20 spacing of the spring fingers 11^a and the notches 13 in this form of my invention is substantially the same as that of the preferred form of my invention, that is, there is either one more or one less spring finger 25 11^a than notches 13 in the arc spanned by the spring fingers. This arc comprises the angle between the radial lines A and B in Fig. 3, in which there are 6 spring fingers and 7 notches. The notches 13 are equally 30 spaced about the entire periphery of the drum, and the spring fingers 11^a are equally spaced through the angle A—B. Thus the drum 5 may be adjusted to any position by very small increments without turning the 35 controller shaft 1.

From the foregoing, many of the advantages of my invention will be apparent. It should be noted that the spring locking fingers 11 always have a tendency to engage a 40 notch 13 when a notch comes in line therewith. Consequently, if none of the spring fingers 11 engage a notch 13 due to careless assembly, adjustment, or for some other reason, only a very small displacement of 45 the drum 5 on the shaft 1 can occur until one of the fingers will engage a notch. Further, if one of the spring fingers 11 or projections 12 should break, the drum 5 could only shift from this adjusted position 50 one increment of the adjustment until the next finger 11 would engage its notch 13. Therefore, my novel locking means is not only easily adjustable in very small steps, but is also automatic in its locking action, 55 in its several different positions, thereby preventing the drum 5 from becoming entirely loose on the shaft 1 in case the drum is not properly adjusted so as to bring a finger 11 opposite a notch 13, or in case the 60 65 particular finger in a notch should happen

to become broken in use. This feature is of particular value in circuit controllers for railway signaling systems where a failure or breakage of the fastening connection between the drum 5 and the shaft 1, if it 70 should allow the drum to shift to any great extent out of its proper position, might result in a serious accident on account of the opening or closing of a circuit at the wrong time. 75

Further, it is quite common for a built up controller drum to have a plurality of contact segments of the same length about the periphery of the drum, but spaced differently about the shaft. With my novel 80 fastening means such drums may be made standard, that is, all alike, and when assembled may be properly positioned on the shaft. By using adjustable drums of this kind the construction of the shaft does not 85 require the usual accuracy. For instance, if a shaft be used having a squared end for fastening the driving means thereto, the keyway to which the adjustable fastening means of the drums is slidably secured, need 90 not have any definite relation to the squared end, but may be cut anywhere about the periphery of the shaft. By thus standardizing the individual drum construction, very 95 few parts are necessary to construct a large variety of controllers, and the necessary stock on hand and repair parts which should be kept in reserve, is reduced.

The reinforcing disk 7 is primarily intended to provide a strong inwardly extending projection 8 to engage the keyway 9 in the shaft 1, but may be omitted by providing a suitable slidably engaging means between the spring locking member 10 and the shaft 1 of sufficient strength and rigidity. The end of the drum 5 opposite the locking notches 13 has been shown as rabbeted to provide clearance for bending the fingers back free of the notches, but such rabbeting may be omitted and clearance 100 provided in any other suitable way. 105

Although I have particularly shown and described different specific embodiments of my invention; nevertheless, I desire to have it understood that the forms selected are 110 merely illustrative and do not exhaust the possible physical embodiments of the idea of means underlying my invention. 115

What I claim is:—

1. In an adjustable rotary circuit controller, a shaft, a drum loosely mounted on said shaft and provided with a plurality of equally spaced notches, and means fastened to said shaft and provided with a spring finger adapted to engage one of said 120 notches.

2. In an adjustable rotary circuit controller, a shaft, a drum loosely mounted on said shaft, a member fastened to said shaft, said drum and member having recesses and 125 130

- projections spanning a certain angle, each projection being engageable with a corresponding recess in a certain relative position of said drum and member, there being a difference of one in the number of recesses and number of projections.
3. In an adjustable rotary circuit controller, a shaft, a drum loosely mounted on said shaft and provided with a plurality of 10 equally spaced notches entirely about the periphery, and means fastened to said shaft and provided with equally spaced fingers adapted to engage said notches, said fingers extending only partly about the periphery.
4. In an adjustable rotary circuit controller, a shaft, a drum loosely mounted on said shaft, and a member rotating with said shaft, said drum and member having portions adapted to interlock and having relative spacing like a vernier.
5. In an adjustable rotary circuit controller, a shaft, a drum loosely mounted on said shaft, a reenforcing member fastened on said shaft, and a spring finger projecting 25 from said member, said drum being provided with notches to selectively receive said finger.
6. In an adjustable rotary circuit controller, a shaft, a drum loosely mounted on 30 said shaft, and a member fastened to said shaft and having a plurality of spaced projections, said drum being provided with a different number of notches, a certain notch receiving one of said projections when said 35 drum and member have a corresponding predetermined relation.
7. In an adjustable rotary circuit controller, a shaft, a plurality of drums loosely mounted on said shaft, and means including 40 a spring finger to adjustably secure each drum to the shaft, said means being adjustable without impairing the adjustment of any other drum.
8. In an adjustable rotary circuit controller, a shaft, a plurality of adjacent 45 drums loosely mounted on said shaft, a member for each drum fastened to the shaft, and means to adjustably secure each member to its respective drum, said means being operable without separating the drums.
9. In an adjustable rotary circuit controller, a shaft, a plurality of adjacent 50 drums loosely mounted on said shaft and provided with engaging means, and a projecting spring finger for each drum extending from the shaft for engaging said means, the end of said finger being accessible so
- that it may be disengaged without separating the drums.
10. In an adjustable rotary circuit controller, the combination with a shaft and drum thereon, of means automatically tending to establish a locking connection between the drum and shaft in any one of a plurality of different positions.
11. In an adjustable rotary circuit controller, the combination with a shaft and drum thereon, of means comprising differently spaced projections and recesses for fastening the drum and shaft in any one of 70 a plurality of different positions, there being one of said projections positioned to engage one of said recesses for each of said plurality of projections.
12. In an adjustable rotary circuit controller, a shaft, a plurality of drums on the shaft, each having in one end a number of projections forming notches, and a member between adjacent drums having a plurality of spring fingers tending to engage in 80 said notches, the ends of said fingers being accessible to permit the fingers being pressed back clear of the projections.
13. In an adjustable rotary circuit controller, a shaft, a plurality of drums, means 85 between adjacent drums for adjustably connecting each drum to the shaft, said adjusting means including spring fingers tending to cooperate with the drums, and means on the shaft for pressing the drums together.
14. An adjustable rotary circuit controller of the type in which individual engagement between any one of a plurality of adjacent drums may be adjusted with respect to the shaft without disturbing the 95 adjustment of any other drum comprising, a shaft, a plurality of drums rotatably mounted on said shaft, members mounted between said drums and splined to said shaft to permit endwise but not rotatable movement 100 relative to said shaft, and means for fastening each of said members to its corresponding drum with any one of a plurality of points equally spaced angularly around the member opposite to any one of a plurality of points equally but differently spaced angularly around said drum, whereby the drum is adjustable relative to the shaft by angular increments equal to the difference in the spacing of said points on 110 the drum and member respectively.

In testimony whereof I hereby affix my signature.

RICHARD C. LEAKE.
